RING MOUNTING

Walter L. Bridler, Detroit, Mich., assignor to
Wright Kay and Company, Detroit, Mich., a
corporation of Michigan

Application September 29, 1931
Serial No. 565,779

7 Claims. (Cl. 63—15)

This invention relates to ring mountings for precious stones, and has for its object an improved disposition of the component parts of such an article, adapted to permit its use either 5 complementarily with another jewel-mounted ring or with a plain band or wedding ring, without interference with or displacement of either from a position of true perpendicularity to the axis of the finger, which in the past has served 10 as an objection to the use of more than one ring upon the same finger.

Rings serving as mountings for precious stones, whether of the solitaire type or of a contour for supporting a plurality of ornately arranged 15 precious stones, have in the past been so constructed that, viewed lengthwise of the plane of the ring, the exposed or stone-supporting portion has been positioned substantially centrally of the general plane of the annular shank or 20 finger-encircling part as such. Of course if only one such ring is to be worn upon one's finger, the lateral extent of such a stone-supporting portion, on either side of the plane of the ring as a whole and lengthwise of the finger, is a 25 matter of no consequence or objectionability. But if the ring were worn in association with a plain band or wedding ring, or on the same finger with another stone-mounted ring, the lateral projection of the mountings forming a part of 30 the metal of each ring, or in some cases the precious stone itself, would result in one or the other of the rings being forced into a position of oblique angularity relatively to the axis of the finger as a whole, or else the crown or stone- 35 supporting part of the ornamental ring would have to be made so high that its laterally extending part would rise beyond the periphery of the plain band ring as such. The tendency in ring 40 design being toward avoidance of such a large outward extent of the stone-supporting part of a jeweled ring, so as to give the appearance of close juxtaposition to the finger, it has become necessary, as a condition precedent to the avoidance of the angular positioning of the rings on 45 the finger, that a marked departure from the constructional forms hitherto followed be indulged in. A further feature of desirability as to my improved ring lies in the fact that there being no projection of the stone or of its mounting 50 over the correspondingly positioned portion of the plain band ring, it is at all times as fully exposed to view as though no jeweled or ornamental ring were on the finger. My improvement is illustrated in the accompanying drawing, in which

55 Figure 1 is a side or edge elevational view of a

jewel-supporting ring, with an adjacently positioned plain band ring and the supporting finger indicated in dotted lines.

Figure 2 is a plan view of such a ring, with the adjacently positioned plain band ring shown 60 in dotted lines.

Figure 3 is an axially lengthwise elevational view of such a ring.

Figure 4 is an edge elevational view of two adjacently positioned jewel-supporting rings, 65 bringing out the possibility of their use together on the same finger without interference of their laterally projecting parts.

Figure 5 is a plan view of the two jewel-supporting rings shown in Figure 4, designed to bring 70 out the same idea as to these as is embodied in Figure 2 in the association of a jewel-supporting ring and a plain band ring.

A indicates in dotted lines an ordinary plain band or wedding ring, and B similarly in dotted 75 lines the outline of a finger whereon the former is worn, while C indicates the plain face or terminal edge of the shank of a finger ring E, whose slightly oblique opposite terminal edge D would not, if positioned against the plain band ring A, 80 enable these rings to both lie in planes truly perpendicular to the axis of the finger and to the shanks of these rings. While the angularity of the face D of the shank E is, in Figures 1 and 4, possibly exaggerated somewhat, it is a fact of 85 common knowledge that generally speaking the shank of a ring whose exposed base, as F, is designed to hold a stone or ornamental design does taper somewhat as that part of the circle of the shank diametrically opposite the head is 90 approached. Even were this not the case, if the head projects on the side C to anything like the degree that is shown projecting on the side D, or indeed to any degree whatever unless beyond the outer peripheral line of the plain band ring 95 A, such angular relative positioning of these two rings would necessarily occur, whereas both for considerations of comfort and appearance it is desirable that the planes of the shanks of both rings be perpendicular to the axis of the finger 100 and of the shanks.

I therefore position all of the stone-carrying head F, insofar as its breadth viewed lengthwise of the finger's axis is greater than that of the shank of the ring similarly viewed, entirely on 105 one side thereof as, for example, the same side as the terminal edge D. The actual resultant displacement of the precious stone or ornamental design upon the exposed face of the ring head F is so slight as regards the plane of the shank 110

F as a whole as to be negligible and unnoticeable when the ring is in position on the hand, especially when worn in association with the plain band ring A, and yet the wholly plain character 5 of the terminal edge C of the ornamental ring is such as to afford no interference with the accurate parallel fit of one against the other, when positioned on the finger, both lying in positions of true perpendicularity with respect to 10 the axis of their respective shanks and of the supporting finger. And whatever be the setting, the prongs or stone-anchoring pieces G may be so positioned on the ring head F as to appropriately position and hold in place such stone or 15 other setting as may be chosen.

In case, instead of wearing such a ring in association with a plain band ring, it is desired to wear two of them, as for example, M and N, with their respective plain faces adjacent one 20 another, a very desirable and pleasing marquise effect may be had from the association of the rings in the manner illustrated in Figures 4 and 5, either being obviously replaceable at will in favor of a plain band ring which will similarly 25 fit with true perpendicularity in the manner illustrated in Figures 1 and 2. It is of course obvious that the contourings herein shown for the head or stone-supporting part of the ring are 30 illustrative only, in no way intended to restrict the scope of this disclosure, provided that that edge or end surface of the ring which is intended to engage or be adjacent to either the plain band ring's terminal edge or the complementarily contoured edge of a similar jewel-supporting ring, 35 be of the character described.

What I claim is:

1. In an ornamental ring, in combination, a shank portion, an integral stone-supporting enlargement positioned partly in circumferential 40 alignment with the shank but projecting laterally from one side only thereof, the opposite side of the shank and enlargement lying in a common plane perpendicular to the axis of the ring.

2. An ornamental finger ring comprising, in 45 combination with a shank portion, one axially terminal face of which is located in a plane perpendicular to the axis thereof, an integrated display portion part of which lies within the plane

50

70

75

of the shank as a whole on the opposite side thereof from its described axially perpendicular face.

3. An ornamental finger ring, comprising, in combination with a shank portion, a stone-supporting display portion which, as the ring is viewed along a line perpendicular to the axis of the display portion, is located preponderantly on one side of the plane thereof, though lying partly in circumferential alignment with adjacent portions of the shank, the shank and display portion having a common face perpendicular to the axis of the ring.

4. A finger ring having an ornamental enlargement wider than the shank measured along the axis of the latter though lying partly within and projecting from one side only of the plane of the ring as a whole, the opposite marginal edge of the shank lying in a plane truly perpendicular to the axis of the ring.

5. As a new article of manufacture, a ring having an integral shank portion and ornamental enlargement, one terminal edge of the shank including an edge of the ornamental enlargement, the ornamental enlargement lying partly within the general plane of the shank of the ring but projecting laterally on the side of the other terminal edge thereof.

6. As a new article of manufacture, an ornamental ring having an ornamental portion of greater breadth than that of the shank measured lengthwise of the axis of the latter, one marginal edge of both the shank and ornamental portion lying in a common plane truly perpendicular to the axis of the ring and the excess breadth of the ornamental portion forming the boundaries of the other marginal edge.

7. An ornamental finger ring characterized by the true perpendicularity of one of its axially terminal faces to the lengthwise axis thereof, and by the presence of part of the physical mass of its setting within the plane of the shank as a whole and entirely on the opposite side of the plane of said perpendicular face from that designed to be engaged by the adjacently positioned plain band ring.
